HEATING DRUM

Filed Sept. 26, 1934

FIG. 1.

Fig. 2.

The diagram illustrates a heat exchanger assembly. It features a central vertical pipe, labeled '2', which is connected to four horizontal heat transfer sections. These sections are labeled '1', '2', '3', and '4' from top to bottom. Each horizontal section is composed of a series of parallel vertical fins, labeled '11', and a central tube, labeled '13'. The entire assembly is shown within a rectangular frame, with arrows indicating the flow direction of the heat transfer fluid.

HEATING DRUM

Samuel G. Gilleland, Parsons, Kans.

Application September 26, 1934, Serial No. 745,585

1 Claim. (Cl. 257—166)

This invention relates to heating appliances of that class which employ drums between the combustion chamber and chimney for radiation of heat and for heating air and circulating it within the room occupied by the drum, and my object is to produce a drum as an attachment for a heating or cook stove, which operates efficiently and is of simple, durable and economical construction.

10 A further object is to produce a drum in which the products of combustion are, in normal operation, compelled at their point of maximum heat, to impinge against and travel downward upon air ducts, so that the temperature of the air circulating up through the ducts shall be highest at or near the upper or discharge ends of the ducts and relatively low at the lower ends of the ducts, it being noted that by this opposed flow of the products of combustion and air, a smaller proportion of the heat units of the fuel burned, are lost through the chimney, and the heating of a room is not only accelerated, but effected at a lesser cost of fuel.

25 More specifically, my object is to produce a drum containing air ducts, running from bottom to top, an inlet opening forward and a discharge opening rearward of the air ducts, and a damper adjustable to permit the products of combustion to pass directly from the inlet to the discharge opening in the desired volume for starting operation, or to compel practically the entire volume to descend within the drum for more extended and longer contact with the air ducts, and for therefore more highly heating and accelerating the circulation of air up through such ducts.

30 To accomplish the objectives mentioned, the invention consists in certain novel and useful features of construction and organization as hereinafter described and claimed; and in order that it may be fully understood, reference is to be had to drawing, in which:—

Figure 1 is a broken top plan view of a heating stove embodying the invention.

Figure 2 is a vertical section on the line II—II of Figure 1.

Figure 3 is a plan view with the top plate omitted.

Figure 4 is a vertical cross section on the line IV—IV of Figure 1.

50 Figure 5 is a perspective view of the form the drum may take when used as an attachment for a stove.

Referring to the drawing in detail, 1 indicates a drum of rectangular or other suitable form, adapted to constitute an integral part of an at-

tachment to a heating stove or as a heating attachment for a cook stove. In either use, the drum is provided with a heat chamber 2 and inlet and discharge openings 3 and 4, for the flow of the products of combustion from the former to the latter through the heat chamber, and in the preferred construction, the opening 3 is in proximity to the top of the drum and the opening 4 is in the top itself.

5 A damper is disposed within the drum and is adjustable to accommodate a direct flow of products of combustion from the inlet to the discharge opening or to prevent a direct flow and establish an indirect flow between said openings. As shown, the damper 5 is spaced above the bottom of the drum and at its lower end is secured upon a cross rod 6, journaled in the sides of the drum so that by grasping one end, it can be turned from a vertical to an inclined position. In the former position, it contacts the top of the drum to shut off direct flow of products of combustion from the inlet to the discharge opening. In the inclined position, see dotted lines, it opens up communication between said opening to accommodate the direct flow mentioned. By spacing the damper from the bottom of the drum an intermediate opening 7 is provided through which the products of combustion must pass when the direct flow is prevented by the damper when occupying a vertical or substantially vertical or closed position. It will thus be apparent that under the condition last mentioned, the products of combustion are compelled to travel downward through the drum from the inlet to the intermediate opening.

35 The drum is provided with one or more air ducts 8 for circulating air through the heat chamber from a point below to a point above the drum, this travel of air being counter or opposite to that of the flow of the products of combustion, especially when the damper is in closed position. As a result of thus providing opposed flows, the products of combustion lose heat in their downward travel while the heating of the air is intensified in its upward flow. It has been found that practically all of the heat units of the products of combustion as the latter enters the drum are extracted by the time escape is made through the discharge opening and that in consequence, the temperature of a room can be raised to a higher degree and in less time and at less cost for fuel, than by any heating appliance or drum using the same character of fuel, through which the air flows in the same direction or merely cross-wise of the travel of the products of combustion.

bustion. For convenience in cleaning the interior of the drum of adhering soot, the back wall has an opening 9 at its lower end, and a door or removable slide 10 serves as a closure for said opening.

5 Where the drum is to be employed as an attachment to a heating or cook stove, the smoke flue from the stove will be connected to discharge opening 3, but where the drum is an integral part of the stove, the latter will have a combustion chamber 11 forward of the opening 3.

10 In the construction formed integrally with the drum, the back wall of the fire box 11, terminates short of the top plate to provide the inlet opening 3. The stove may be adapted for burning solid or other types of fuel, and for burning wood or coal, preferably has a large door-controlled opening 12, a grate 13, a bottom draft control means, such as a slide 14, and a top draft control 15 means, such as a slide 15. There will also be supporting legs 16 or the like to provide for free circulation of air up through the air ducts.

15 From the above description and drawing, it will be apparent that the invention possesses the features of advantage set forth as objectives, and

that the structure may be modified in various particulars without departure from the principle of construction involved and the scope of the appended claim.

5 I claim:—

An air heating drum, comprising a casing having spaced inlet and outlet openings in its upper portion for products of combustion, and a series of air-ducts extending through the casing between said openings and open to receive air below and discharge it above the casing, and a damper within and pivoted at its lower end to opposite side walls of the casing above the bottom of the latter and in a vertical plane between the air ducts and said outlet opening, and adapted to 10 be swung to dispose its upper end against the back wall of the casing to prevent the flow of the products of combustion to the outlet opening by passage back of the damper, or to stand vertically 15 back of the air ducts and form a partition compelling the products of combustion to reach the outlet opening only by passing below and then 20 upwardly at the rear side of the damper.
